UNITED STATES PATENT OFFICE.

WILLIS M. FOLLMER, OF NEW YORK, N. Y.

DESIGN FOR A HANDLE FOR UMBRELLAS OR PARASOLS.

55,264.

Specification for Design.

Patented May 25, 1920.

Application filed December 3, 1919. Serial No. 342,274. Term of patent 7 years.

To all whom it may concern:

Be it known that I, WILLIS M. FOLLMER, a citizen of the United States, and a resident of the city, county, and State of New York, have invented a new, original, and ornamental Design for a Handle for Umbrellas or Parasols, of which the following is a specification, reference being had to the accompanying drawing, forming a part hereof.

The drawing shows a perspective view of the handle as attached to a parasol.

The design is especially characterized by the disk 1 which surrounds and is affixed to the stem 2 of the handle.

I claim:

The ornamental design for a handle for umbrellas or parasols, substantially as shown and described.

WILLIS M. FOLLMER.
